UNITED STATES PATENT OFFICE.

EDMUND M. ERB, OF JERSEY CITY, NEW JERSEY, ASSIGNOR TO ROBERT M. DIXON, OF EAST ORANGE, NEW JERSEY.

WINDOW CONSTRUCTION.

No. 821,228.

Specification of Letters Patent.

Patented May 22, 1906.

Application filed December 28, 1905. Serial No. 293,566.

To all whom it may concern:

Be it known that I, EDMUND M. ERB, residing at Jersey City, in the county of Hudson and State of New Jersey, have invented certain new and useful Improvements in Window Constructions, of which the following is a full, clear, and exact description, such as will enable others skilled in the art to which it appertains to make and use the same.

This invention broadly relates to window constructions, but more particularly it concerns improvements in windows which are ordinarily subjected to severe usage, such as in railway-cars, boats, or other units of transportation.

This invention has in view, among other objects, a mechanism which will positively hold a sash in any raised position and which may be so released by a slight pressure of the fingers that the sash may be freely adjusted to any other position.

Another object of this invention is to formulate a means for facilitating the positioning of window-sashes in their frames in such a manner that they will be positively secured in place and remain undisturbed notwithstanding the vibrations of the car or other structure by which they are carried.

Another object of this invention is to devise an instrumentality whereby the elimination of all binding friction at the sides thereof will be completely effected during the raising or lowering of a sash.

Another object is to produce a sash-affixing means which is simple in structure and composed of few parts, all of which are adapted for being made at a modicum of cost and so formed individually as to be capable of being readily assembled into a neat and compact arrangement susceptible of effective use in accomplishing the purposes intended.

Other objects and advantages will be in part obvious and in part pointed out hereinafter.

With these and other ends in view this invention accordingly consists in the features of construction, combinations of parts, and arrangement of elements hereinafter more explicitly set forth as an exemplification of the underlying principles involved in the invention.

In order that this invention may be more fully understood and made clearly comprehensible to others skilled in its relating arts,

drawings illustrating one embodiment of the same are appended as a part of this specification, and while the underlying principles of the invention may be otherwise applied by modifications falling within the scope of the claims the herein-stated form is preferably employed in ordinary practice and is regarded as a substantial improvement over the many implied and obvious variations of the same.

In the drawings it will be observed that like numerals denote corresponding parts throughout all the figures, of which—

Figure 1 is a sectional perspective to the rear of a window construction embodying the invention, parts being broken away to more clearly show certain details. Fig. 2 is a front elevation with parts removed, showing the adopted arrangement of the various features. Fig. 3 is a section in a transverse plane intersecting along line 3 3 of Fig. 2. Fig. 4 is an end elevation of Fig. 2, partly in section, showing the arrangement of the parts when operative to lock the sash against sliding with respect to the frame. Fig. 5 is a view similar to Fig. 4, but showing the parts as released to freely permit a sliding of the sash. Fig. 6 is a vertical sectional view of the releasing mechanism as taken along line 6 6 of Fig. 2. Fig. 7 is a section taken along line 7 7 of Fig. 2 to show certain details of the release for the positive lock.

In carrying out the invention, some suitable means operative to securely position a sash in its frame will be employed. For this purpose the instrumentality disclosed in a copending application, Serial No. 248,100, will be found to be most effective in use; but it is to be understood that the application of the herein-described invention is not limited to any particular sash-securing mechanism, as it may be employed in connection with certain other forms. Since, however, it is preferable to use the same in the herein-described arrangement, it will be convenient to describe it in such relation. To this end a casing 1 forms a part of the frame within which the sash slides and is provided with a vertically-extending rib 2 at one side thereof, whereby the casing is L-shaped in cross-section, as shown. The sash is of a U-shaped cross-section, the front and rear sides thereof being respectively indicated by 3 and 4. Such sides embrace or straddle the protruding rib 2 of the frame, and the lateral rela-

tionship is such that side 4 will normally slide in contact with such rib. Means are also provided for normally pressing together rib 2 and side 4 with a sufficient force to afford enough friction therebetween to prevent any sliding whatever whenever it is desirable to have the sash and frame be so secured together. The means, which is in the nature of a clog, may also conveniently afford friction between other moving surfaces. Ordinarily it will be best to locate this means within the space between side 3 of the frame and rib 2, and it is thus shown by the drawings. In this embodiment such means consists of a shoe 5, which is slidably carried by the sash and adapted to be brought with considerable force against rib 2, so as to securely clamp the same between such shoe and the outer wall 4 of the sash. As will be comprehended, this mechanism constitutes a clog or friction-affording member which is so mounted that by a movement thereof or of certain features thereof it will be brought firmly into a sash-securing position. This action may be realized in various ways, but that shown is regarded as the most improved type and consists in movably mounting the clog on the sash and utilizing cam-surfaces in such a manner that a movement of the clog in a vertical direction or of any part thereof will set up sufficient friction to positively retain the sash in any desired place in the frame. Thus, as shown, the shoe is provided with an inclined slot 6, within which slides a stud 7, which protrudes from the sash. Obviously a downward movement of the shoe or clog will clamp the sash in place, while, on the contrary, an upward movement thereof will release the same. It is to be noted in this connection that to all practical purposes such releasing action entirely eliminates all of the binding friction between the sash and the frame and that the former may be freely raised when so released. A mechanism is provided for normally keeping the clog in effective state, usually by means of an elastic yield provided by springs, such as 8 and 9.

The gist of this invention resides more particularly in a means for rendering the afore-said or other sash-affixing mechanism operative or inoperative, as may be desired. As will be clear, it is highly desirable that the adopted means be both effective and easy in actuation. This invention contemplates a means whereby a movement of the fingers, such as a horizontal motion, will be transformed into an actuating clog movement, which, as shown in the now-described illustrative embodiment, may be vertical. To this end an extension 10 from the clog means is pivoted to a revoluble rod 11, the latter being cranked, as shown by 12, whereby a rotary movement of such rod may be transformed into the desired reciprocatory movement of the clog. The revoluble rod 11 is so mounted

in the lower part of the sash as to be incapable of a longitudinal movement, being retained in place by means of suitable bearing-plates 13.

To render the rod or actuator-rod 11 adaptable to being conveniently actuated through manual manipulation, it is preferred to resort to a simple interposed link work, which may now be described.

A bell-crank lever 15 is pivoted to swing about an axis transversely disposed with respect to that of the revoluble rod 11 and is provided with a hook-shaped arm 16 in engagement with the cranked portion 14, provided by said rod. At the end of its other arm such bell-crank lever is in engagement with the rear end 18 of a finger-lever 17. The finger-lever swings about a vertical axis, being pivoted to the lower part of the sash at a point 19 intermediate its length in order that a motion of the finger end 17 will result in a contrary motion at the bell-crank-lever-engaging end 18. Adjacent this finger-lever 17 is a companion finger-lever 20, the latter serving, as here shown, to actuate a positive lock in co-operation with the friction lock or clog above referred to. These finger-levers normally have their exposed ends spaced apart, being urged into such position by means of a retractile spring 9. When so positioned, as shown by Fig. 2, the sash is in an immovable relation with respect to the frame, but when the ends are brought into proximity by the fingers, as shown in Figs. 1 and 5, the clog is no longer effective and the sash may be freely raised or lowered within the frame. This motion may be readily followed by means of the arrows shown in Fig. 1, from which it will be seen that as a consequence of bringing together the exposed ends of the finger-levers the clog 5 will be raised and retracted from the rib 2.

The positive lock acting in conjunction with the friction-lock consists in this embodiment of a pair of longitudinally-slidable bars 21 and 25, having ends adapted to engage with suitable studs, as that shown by 22. Bar 21 has its inner end inturned, so as not to interfere with the revoluble rod, and pivoted at 23 to the lower end of lever 24. The corresponding bar 25 extends from the opposite side of the sash into a pivotal connection 26 at the upper end of lever 24, the fixed pivot of which lies intermediate the connection with the lock-bars. Finger-lever 20 is in engagement with the upper end of such lever at point 27. It will now be observed that a reciprocation of lever 20 toward its companion lever 17 will so swing the bars as to withdraw them from under studs 22, and upon release of the fingers from such levers spring 9 will at once draw them together at their inner ends and bring both the positive and the friction locks into operative position.

It will thus be seen that a mechanism has been provided which is well adapted to accomplish the several objects of this invention. By arranging the finger-levers in the shown bifurcated manner it becomes possible to simultaneously operate both the friction and the positive locking means by a simple closure movement of the fingers, and because of the positive interlinking between the various features of this invention such simultaneous action is insured. Furthermore, since the bearing parts are substantially all entirely pivotal in nature but little friction is afforded by the operation of the release. Substantially the entire pressure of the fingers is accordingly transmitted directly to the clog and the operation of the latter is rendered the more effective both with respect to the release and the forward throw thereof.

As many changes could be made in the above construction and many apparently widely different embodiments of my invention could be made without departing from the scope thereof, I intend that all matter contained in the above description or shown in the accompanying drawings shall be interpreted as illustrative and not in a limiting sense. I desire it also to be understood that the language used in the following claims is intended to cover all of the generic and specific features of the invention herein described and all statements of the scope of the invention which, as a matter of language, might be said to fall therebetween.

Certain features shown in the drawings are shown, described, and claimed in my application, Serial No. 284,110, filed October 23, 1905, and therefore are not claimed herein.

Having described my invention, what I claim as new, and desire to secure by Letters Patent, is--

1. In combination, a frame, a sash or the like mounted to slide therein, a member arranged between the sash and the frame adapted by its frictional engagement with the frame to hold the sash stationary in any position in its range of movement, revoluble means for vertically reciprocating said member to release the sash and permit free sliding, and a lever connected with said revoluble means adapted by movement in a horizontal direction to actuate the same.

2. In combination, a frame, a slideable sash or the like mounted therein, a member arranged between the sash and the frame, means for normally holding the said member in engagement with said frame to maintain the sash in any desired position within its range of movement, revoluble means for vertically reciprocating said member to release said sash and permit free sliding, and a lever connected with said revoluble means adapted by movement in a horizontal direction to actuate the same.

3. In combination, a frame, a slideable sash

mounted therein, a member arranged between the sash and the frame and normally held in frictional engagement with the frame by spring-controlled means to hold the sash stationary in any position in its range of movement, revoluble means for vertically reciprocating said member to release the sash and permit free sliding, and a lever connected with said revoluble means adapted by a movement in a plane substantially at right angles to the movement of said member, to actuate said revoluble means.

4. In combination, a frame, a sash slideably mounted therein, a member carried by the sash which engages the frame frictionally and thereby holds the sash against sliding from any position to which it has been slid, a revoluble member having a crank adapted when actuated to vertically reciprocate said member and thereby release the sash and permit of free sliding, and a finger-lever pivoted for horizontally swinging on the sash and adapted when swung to actuate said revoluble member.

5. In window construction, in combination, a frame, a sash or the like mounted to slide therein, a member carried by said sash adapted by a movement relative thereto to force said sash into engagement with said frame thereby to restrain the movement thereof from any position in its range of movement, a revoluble rod having connection with said member adapted to reciprocate said member whereby the sash is freed from its frictional engagement with the frame and permitted a free sliding movement therein, and a lever mounted upon the sash and adapted to swing horizontally thereon, said lever being connected to and adapted for actuating said rod.

6. In window construction, in combination, a sash, a frame in which said sash is mounted to slide, a member loosely carried by said sash adapted by a movement relative thereto to force the same into engagement with a portion of said frame whereby said sash is normally restrained against sliding, spring-controlled means for normally urging said member to relative movement with respect to said sash whereby said sash is normally maintained against sliding, a revoluble rod for reciprocating said member thereby to release said sash to permit of free sliding, and a lever mounted to swing horizontally on said sash having connection with said actuator adapted to rotate the same and reciprocate said member.

7. In window construction, in combination, a frame, a sash or similar device adapted to slide in said frame, a member mounted loosely upon said sash adapted to be moved relative thereto whereby said sash is normally held in frictional engagement with a portion of said frame and prevented from sliding therein, spring-controlled means for

normally urging said member to such relative movement, a revolute rod journaled upon said sash adapted to actuate said member thereby to release said sash and permit of free sliding, and a lever pivoted to swing in a direction substantially at right angles to the reciprocating movement of said member connected with said rod adapted when moved to actuate the same and thereby reciprocate said member.

8. In window construction, in combination, a frame, a sash slidably mounted therein, a member provided with an inclined slot carried by said sash and adapted to be moved relative thereto into engagement with a portion of said frame whereby said sash is held in engagement with said frame to frictionally restrain the same against sliding, a device extending from said frame and located in said inclined slot of said member for guiding said member in its movement relative to said sash, a revolute actuator for said member, and a lever connected with said actuator adapted to revolve the same when moved in a direction substantially at right angles to the sliding movement of said sash.

9. In window construction, in combination, a frame, a sash slidably mounted therein, a member provided with a plurality of inclined slots carried by said sash, said slots receiving projections extending from said sash, a revolute actuator engaging said member for normally maintaining the same in engagement with a portion of said frame whereby said sash is frictionally engaged with said frame and restrained against sliding, said revolute actuator being adapted to reciprocate said member from the portion of the frame with which it is normally engaged thereby to release the sash from the frame to permit the sash to slide freely therein, and a lever upon said sash which, by movement at substantially right angles to the movement of said member, is adapted to revolve said actuator and reciprocate said member.

10. In combination, a sash, a frame, a member fixed upon the frame, means adapted by movement relative to said sash to engage said member to force said sash into engagement therewith, and a revolute actuator for said last-mentioned means.

11. In combination, a sash, a frame, a guide fixed upon the frame, means carried by the sash adapted by a movement relative thereto to engage said guide to force said sash into engagement therewith, and a revolute actuator for said last-mentioned means.

12. In combination, a sash, a frame, a member fixed upon said frame extending within said sash, means carried by the sash adapted by a movement relative thereto to engage said member to force said sash into engagement therewith, and a revolute actuator for said last-mentioned means.

13. In combination, a sash, a frame, a

guide fixed upon the frame and extending within said sash, means carried by said sash adapted by a relative movement thereto to engage said guide and thereby force said sash into engagement therewith to frictionally hold the same against movement, and a revolute actuator for said last-mentioned means.

14. In combination, a sash, a frame, a member fixed upon the frame, means adapted by a movement relative to said sash to engage said member and thereby force said sash into engagement therewith, a rotatably-mounted rod for actuating said last-mentioned means, and a finger-lever for actuating said rod at will.

15. In combination, a sash, a frame, a guide fixed upon the frame, means carried by the sash adapted by a movement relative thereto to engage said guide to force said sash into engagement therewith, a revolute actuator for said last-mentioned means, and a finger-lever pivoted upon the sash for revolving said actuator.

16. In combination, a sash, a frame, a member fixed upon said frame extending within said sash, means carried by said sash adapted by a movement relative thereto to engage said member to force said sash into engagement therewith, a revolute actuator for said last-mentioned means, and a finger-lever pivoted upon the sash adapted to revolve said actuator.

17. In combination, a sash, a frame, a guide fixed upon the frame extending within said sash, means carried by said sash adapted by a relative movement thereto to engage said guide and force said sash into engagement therewith, a revolute actuator for said last-mentioned means, and a finger-lever for revolving said actuator.

18. In combination, a sash, a frame, a member fixed upon the frame, means adapted by a movement relative to said sash to engage said member and thereby force said sash into engagement therewith, a revolute actuator for causing movement of said last-mentioned means, and spring means for normally holding said last-mentioned means in engagement with said member.

19. In combination, a sash, a frame, a member fixed upon the frame, means adapted by movement relative to said sash to engage said member and thereby force said sash into frictional engagement therewith, a revolute actuator for said last-mentioned means, and a yielding device acting through said actuator to normally maintain said last-mentioned means in engagement with said member.

20. In combination, a sash, a frame, a guide fixed upon the frame extending within said sash, means carried by said sash adapted by a movement relative thereto to engage said guide to force said sash into engagement

therewith, a revolute actuator for said last-mentioned means, and a spring acting through said actuator to normally maintain said last-mentioned means into engagement 5 with said guide.

21. In combination, a sash, a frame, a guide fixed upon the frame and extending within said sash, a member carried by said sash adapted by a movement relative thereto 10 to engage said guide and force said sash into engagement therewith whereby said sash is normally restrained by friction against sliding in said frame, a revolute rod having a cranked end which engages said member 15 adapted when rotated to reciprocate the same whereby free sliding movement of said sash will be permitted, and a finger-lever mounted upon the sash adapted for rotating said rod.

22. In combination, a sash, a frame, a guide fixed upon said frame extending within a channel arranged longitudinally of said sash, a member adapted automatically to contact with said sash and said guide whereby 25 said sash and said guide are forced into frictional contact to prevent relative movement thereof, and a revolute actuator for said member.

23. In combination, a sash, a frame, a guide fixed upon said frame extending within a channel arranged longitudinally with said sash, a member carried by said sash mounted for movement relative thereto, means for causing said member to engage said guide 35 whereby said sash will be frictionally engaged therewith and restrained by friction against sliding movement, and a rotatably-mounted rod having a cranked connection with said member adapted to actuate the 40 same.

24. In combination, a sash having a longitudinally-extending channel, a frame, a guide fixed upon said frame extending within said channel, said guide being disposed in a parallel relation to the walls of said channel, a movable member carried by said sash and arranged within said channel, means adapted automatically to force said member into engagement with said guide whereby said sash 45 is caused frictionally to be engaged therewith and thereby restrained by friction against sliding, a revolute actuator for said movable member, and manually - controlled means adapted to actuate said actuator.

25. In combination, a sash, a frame, a guide fixed upon said frame extending into a channel arranged longitudinally of said sash, means for positively locking said sash with said frame, means for frictionally locking 60 said sash with said guide, a revolute actuator adapted for moving said frictional locking means, and manually-operated means adapted simultaneously to release both of said locking means, said frictional locking means through said revolute actuator being

adapted automatically to relock said sash with said guide at any point in the range of movement thereof.

26. In combination, a sash, a frame, a guide fixed upon said frame extending into a channel arranged longitudinally of said sash, means for positively locking said sash with said frame, means for frictionally locking said sash with said guide, a rotatably-mounted member adapted for operating said frictional locking means, manually-operated means adapted simultaneously to release both of said locking means, and means acting through said rotatable member for relocking said frictional locking means with said guide 70 at any point within the range of movement with said sash whereby the same is frictionally restrained against movement.

27. In combination, a sash, a frame, a guide fixed upon said frame extending within said sash, means for positively locking said sash with said frame, means for frictionally locking said sash with said guide, both of said locking means being carried by said sash, a revolute actuator for said frictional locking 85 means, devices adapted simultaneously to release both of said locking means whereby a movement of said sash along said guide is permitted, one of said devices acting through said revolute actuator, and means adapted 90 through said revolute actuator to operate said frictional locking means whereby said sash is forced into engagement with said guide at will at any point in its range of movement.

28. In combination, a sash, a frame, a guide fixed upon the frame extending within the recess of said sash, a plurality of locking means carried by said sash, one of said locking means adapted positively to lock said sash with said frame, the other of said locking means being adapted frictionally to lock the same with said guide, a revolubly-mounted member connected eccentrically to said frictional locking means, means adapted simultaneously to release both of said locking means whereby said sash is freely movable, one of said releasing means operating through the means connected eccentrically with said frictional locking means, and means adapted automatically to operate said frictional locking means at any stage of movement of said sash.

29. In combination, a sash, a frame, said sash being provided with a longitudinally-extending channel, a guide fixed upon the frame extending within said channel, said guide being arranged in proximity to one of the walls of said channel, a plurality of locking means carried by said sash, one of which is adapted to lock the same positively with said sash, the other of said locking means being adapted frictionally to lock the same with said guide, a member journaled upon said sash having a portion which is eccentrically 120 125 130

- connected with said frictional locking means, a device carried by the sash adapted through said member to release said frictional locking means, a device carried by said sash adapted 5 to release said positive locking means, said devices being adapted to be operated simultaneously whereby both of said locking means are operated at substantially the same instant.
30. In combination, a sash, a frame, a plurality of positive locks for said sash, a plurality of frictional locks for said sash, a rotatably-mounted actuator adapted to operate both of said frictional locks, and a single device adapted to operate both of said positive locks.
31. In combination, a sash, a frame, a plurality of positive locks for said sash, a plurality of frictional locks for said sash, and single means adapted to release both of said positive locks, a rotatably-mounted member carried by the sash adapted to release both of said frictional locks, said releasing means being capable of being manipulated whereby 25 all of said locks are released simultaneously to allow a free sliding movement of said sash, said frictional locking means being adapted to relock said sash against movement at any stage of said range of movement.
32. In combination, a sash, a frame, said sash being provided with a longitudinally-extending channel in its lateral edge, a plurality of guides fixed upon said frame, one of which extends within each of said channels, 35 a plurality of locking-bolts arranged to reciprocate in opposite directions within said sash, a rocker-lever to either end of which is connected one of said bolts whereby said bolts are reciprocated simultaneously in opposite 40 directions, a single means connected with said rocker-lever for reciprocating said bolts, means adapted normally to maintain said bolts in extended positions a plurality of frictional locking means positioned within 45 said sash, a rotatably-mounted member connected eccentrically with each of said frictional locking means and adapted simultaneously to operate the same, and a single means for causing a rotative movement of said rotatably-mounted member whereby said frictional locking means are operated to unlock 50 the sash and permit a free sliding movement thereof, the means for releasing said positive locking means and the means for releasing said frictional locking means being capable 55 of being operated simultaneously.
33. In combination, a sash, a frame in which said sash is adapted to slide, a guide fixed upon said frame extending within said 60 sash, a frictional locking member provided with an inclined slot mounted for movement upon said sash and normally held in engagement with said guide whereby said sash is held frictionally in engagement with said 65 guide and restrained against sliding, means extended loosely through said inclined slot for connecting said member with said sash, and a rotatably-mounted rod connected with said member adapted, when actuated, to reciprocate said member and thereby cause 70 said member through the engagement of the means extending loosely through the inclined slot thereof with the walls of said slot to be disengaged from said guide thereby disengaging the said sash from the guide to permit free sliding movement thereof.
34. In combination, a frame, a sash mounted to slide in said frame, a guide upon said frame extending within said sash a frictional locking member provided with a plurality of inclined slots, means extending loosely through said inclined slots to connect said frictional locking members movably with said sash, a revolvably-mounted actuator carried by said sash and having connection with 80 said frictional locking member, means connected with said actuator adapted to urge the same in one direction whereby said frictional locking member through the instrumentality of the engagement of the walls of said slots with the means extending therethrough is normally held in engagement with said guide and the sash by its engagement with said guide restrained by friction against sliding, and means adapted to revolve said actuator 85 to disengage said frictional locking member from said guide and thereby prevent a free sliding movement thereof.
35. In window construction, in combination, a sash having a recessed portion, a member projecting within said recessed portion, means positioned between said member and one of the walls of said recess adapted to force apart said wall and said member and force together said member and the opposite wall of said recess, and a revolvble actuator adapted to operate said aforementioned means.
36. In window construction, in combination, a sash having a recessed portion, a guiding member projecting within said recessed portion, means located within said recessed portion adapted to clamp said guiding member and lock said sash against movement in either direction, and a revolvble actuator for 100 operating said aforementioned means.
37. In window construction, in combination, a sash having its lateral portions channeled, guiding members projecting within said channels, means within each of said channeled portions adapted to clamp each of said guiding members and lock said sash against movement in either direction, and a rotatably-mounted rod carried by said sash having cranked connections with said aforementioned means.
38. In window construction, in combination, a sash having its lateral portions channeled, guiding members projecting within said channels, reciprocating means within 110

each of said channel portions adapted to clamp each of said guiding members and lock said sash against movement in either direction, and a revolute rod eccentrically connected at either end to said guiding members from their clamped condition.

39. In window construction, in combination, a frame, a guiding member fixed upon the frame, a slideable sash, portions of which extend about said guide, a member carried by said sash and located therein adapted automatically to be forced laterally to carry said sash into frictional contact with said guide, a revolubly-mounted actuator carried by said sash having connection with said member, and a finger-lever for operating said actuator.

40. In window construction, in combination, a slideable sash provided with a recess, a stationary guide fixed to the frame and extending within said recess, and means located within said recess adapted automatically to force one of the walls of said recess into frictional contact with said guide, an actuator having a pivotal connection with the means located in said recess and adapted to be rotated to release the wall of said recess which is in engagement with said guide to free the sash and permit free sliding, and means for revolving said actuator.

41. In combination, a slideably-mounted sash or similar member having a channeled stile, a frame in which said sash is mounted to slide, a guide fixed to said frame extending within said channel, a friction member carried by said sash and adapted to be moved into engagement with said guide whereby a wall of said channel will be frictionally engaged with said guide, a revolute rod having bearings in said sash which has a crank connection with said friction member so that when the same is rotated said friction member will be disengaged from said guide and the sash thereby released and permitted to slide freely in the frame.

42. In window construction, in combination, a slideable sash or similar member having a channeled edge, a guide extending within the channel in the edge of said sash, a movable member carried by said sash and located in the channel thereof, said guide adapted by a movement of said movable member to be clamped between the same and the flange of the channel in said sash, a revolute actuator journaled in said sash and connected eccentrically with said movable member, and a finger-lever for rotating said revolute member to carry said movable member from said

guide thereby releasing said sash from frictional engagement therewith and permit free sliding movement thereof.

43. In window construction, in combination, a slideable sash or the like provided with a channel in the said stile thereof, a fixed guide extending within said channel, a friction member carried by said sash adapted to be reciprocated within said channel, means adapted automatically to force said friction member into engagement with said guide whereby a wall of said channel will be carried into frictional engagement with said guide and the sash restrained against sliding, a revolute actuator for moving said friction member, a lever for moving said revolute actuator and a spring acting upon said lever adapted to maintain said aforementioned parts in a normal condition whereby the sash is frictionally locked against sliding.

44. In window construction, in combination, a frame, a sash having each of its side stiles provided with longitudinally-extending channels, a pair of guides fixed to said frame, each of which extends within one of said channels in proximity to one of the side stiles thereof, a friction member provided with obliquely-extending slots located in each of said channels, studs extending from said stiles and entering said slots, a rotatively-mounted rod journaled in said sash and provided at either end thereof with cranked extensions connected with said friction members, said rod having a cranked portion intermediate its ends, a lever pivoted to said sash and having an arm which engages said last-mentioned crank portion, a finger-lever for operating said aforementioned lever, and a spring for opposing a movement of said finger-lever, said spring also operating through the connecting mechanism to normally hold said friction members into engagement with said guides whereby the walls of said channels in proximity to said guides will be clamped thereagainst and the sash frictionally held against sliding, said finger-lever when moved in opposition to the tension of said spring being adapted through the aforementioned mechanism to move said friction members thereby disengaging said sash from said guides and permit the same to slide freely in the frame.

In testimony whereof I affix my signature in the presence of two witnesses.

EDMUND M. ERB.
